(57) **CLAIM**

The ornamental design for a “wireless transceiver”, as shown and described.

DESCRIPTION

FIG. 1 is a top, front, and right side perspective view of a wireless transceiver, showing our new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top, front, and right side perspective view thereof. The broken lines in the figures illustrate the portions of the design that form no part of the claimed design.

The additional broken lines shown in FIG. 9 illustrate environment and form no part of the claimed design.

1 Claim, 9 Drawing Sheets
